United States Patent Office

Des. 205,437
Patented August 2, 1966

205,437

PRESSURE REGULATOR, OR THE LIKE

William E. Rhodes, Columbus, Ohio, assignor to Robert-
shaw Controls Company, Richmond, Va., a corporation
of Delaware

Filed May 24, 1965, Ser. No. 85,436
Term of patent 14 years

(Cl. D91—3)

FIG.-1

FIG.-7

FIG.-3

FIG.-5

FIG.-6

FIGURE 1 is a top perspective view of the pressure regulator of this invention;

FIGURE 2 is a bottom perspective view;

FIGURE 3 is a side elevation of the left side of FIGURE 1;

FIGURE 4 is a side elevation of the right side of FIGURE 1;

FIGURE 5 is a rear elevation of FIGURE 1;

FIGURE 6 is a front elevation of FIGURE 1;

FIGURE 7 is a top plan view of FIGURE 1;

FIGURE 8 is a bottom plan view of FIGURE 1;

FIGURE 9 is a bottom perspective view of a modified form thereof, the top and sides being the same as disclosed in FIGURES 1 through 8 inclusive; and,

FIGURE 10 is a bottom plan view thereof.

I claim:

The ornamental design for a pressure regulator, or the like, as shown and described.
